SUCTION SWEEPER

Lloyd W. Pardee, Lakewood, Ohio, assignor to
 The Scott & Fetzer Company, Cleveland, Ohio,
 a corporation of Ohio

Application February 18, 1935, Serial No. 7,000

12 Claims. (Cl. 15—8)

This invention relates to suction sweepers and in particular to the brush drive and brush mounting of a device of the type described.

One of the objects of this invention relates to the provision of an improved form of driving belt pulley for the brush drive of a suction sweeper which pulley is adapted to maintain the belt at all times in its operative position on its pulleys.

A further object of the invention relates to a quickly detachable suction sweeper brush mounting of simple and inexpensive construction having provisions for maintaining the brush bearings in proper alignment; for readily effecting the adjustment of the brush with respect to the working mouth of the sweeper; for reducing the transmission of noise from the brush to the cleaner casing; for facilitating the removal of the brush from the cleaner nozzle; and for readily disassembling the brush bearings for cleaning and other purposes.

With these and other objects in view, the invention consists in the novel construction, arrangement and combination of parts, hereinafter illustrated and described in some of its embodiments in the accompanying drawing, and particularly pointed out in the appended claims.

In the drawing, Figure 1 is a side elevational view, partly in section, of an electrically operated suction cleaner with certain of the parts of the cleaner shown in section to better illustrate the details of this invention; Figure 2 is a detail sectional view taken on line 2—2, Figure 1; and Figure 3 is an enlarged detail sectional view taken on line 3—3, Figure 2.

The suction sweeper illustrated in the drawing, comprises a casing structure including a motor housing 1, a fan case 2 and a suction nozzle 3 arranged one in front of the other in the order named. An electric motor located within the motor housing 1 has its armature shaft 4 extended into the nozzle 3, and at a point adjacent to the outer end of the shaft it is reduced in section to form a pulley 5 for a brush driving belt 6. In forming the pulley 5, an annular flange 7 is left on the end of the shaft to prevent the belt from crawling or sliding off of the pulley 5. Casters 8 are provided for supporting the sweeper casing.

The nozzle 3 is provided with an opening 9 by way of which access may be had to the belt and the belt driving pulley. A removable cover 10 is provided for the nozzle opening 9. The lowermost part of the nozzle 3 is provided with lips 11 defining the suction or working mouth of the cleaner. A brush 12 is rotatably supported in

the nozzle of the sweeper immediately above the working mouth thereof and it is provided with a pulley face intermediate its ends below the motor armature shaft 4 and the pulley 5 formed on the end thereof. The cover 10 is provided with spring clips 9^a, 9^b by means of which it is held in place over the nozzle opening 9. The cover 10 is also provided with an offset lip 9^b adapted to be engaged by the finger of the user for facilitating the removal of the cover.

Due to the provision of the flanged end 7 on the pulley 5, it is possible to locate the pulley of the brush 12 with its axis a substantial distance ahead of the center of the driving pulley 5 instead of directly below the same as is the customary arrangement. This permits the locating of the working mouth of the cleaner a greater distance forwardly of the cleaner than has heretofore been considered possible or feasible to do, and by reason of the arrangement of the parts just described, the front face of the cleaner nozzle may be sloped backwardly a considerable amount to the enhancement of the appearance of the cleaner casing.

The detachable brush mounting and the details of the brush bearing are illustrated best in Figure 3 of the drawing. At each of the ends of the nozzle 3, there is provided an inwardly extending boss 13 adapted for the adjustable reception of a threaded brush supporting post or pin 14, having a flange 15 intermediate its ends and a slotted head 16 at its outer end. A sleeve 17 formed from a yielding elastic material, as for example soft rubber, is carried on the unthreaded portion of the post member 14.

The brush 12 is formed with an axial bore 18 extending the length of the brush for reception of a rod 20. The ends of the rod are each received in identical brush supporting members 21. The inner parts 22 of these members engage with the inner races of anti-friction bearings 23. The outer race of each of the bearings 23 is snugly received within a cylindrical sleeve 24 and the inner end of which is formed at its edge with a shoulder for receiving a cap 25 having a central aperture for reception of the rod 20.

A lubricant retaining, dust excluding washer 26 is carried in an annular space defined by the brush supporting member 21, the bearing 23 and the cylindrical sleeve 24. The outermost end 27 of the brush supporting member 21 is in the form of a U-shaped extension which embraces and engages the rubber sleeve 17 when the brush is in its operative position, the brush being held

in place by reason of the frictional engagement of the parts just described, and in this connection, the belt 6 also tends to maintain the brush in proper position.

5. Adjustment of the brush with respect to the mouth of the sweeper may be readily effected by simply rotating the threaded brush supporting posts 14 in the desired direction. Upon removal of the belt 6 from the driving pulley 5 by way of 10 the nozzle opening 9, the brush and belt may be readily removed from the cleaner nozzle. After the brush has been removed from its supporting posts, the brush supporting members 21 may be readily removed for permitting cleaning and lubricating the brush bearings 23. These bearings are frictionally fitted into the ends of the brush and their replacement, when necessary, may be readily effected.

The foregoing details of construction illustrating a preferred form of the invention, disclose a simple form of adjustable brush mounting having provisions for the easy and ready removal of the brush, with means to maintain the brush bearings in proper alignment, including means 25 for insuring proper lubrication of the brush bearings while at the same time excluding dust and dirt therefrom, and means for permitting the inspection, cleaning and lubricating of the brush bearings as well as means for permitting their 30 ready removal and replacement if necessary.

Furthermore, it is to be understood that the particular forms of suction sweeper shown and described, and the particular procedure set forth are presented for purposes of illustration and 35 explanation and that various modifications of said apparatus and procedure may be made without departure from the invention as defined in the appended claims.

Having thus described my invention what I 40 claim is:

1. In a suction sweeper, a suction nozzle, a brush rotatably mounted therein, and means for frictionally securing said brush in operative position in said nozzle, said means including a downwardly extending post part and a flexible yielding material interposed between the brush and post for frictionally holding the brush in place while at the same time preventing the transmission of sound and vibration to the cleaner 50 nozzle.

2. In a suction sweeper, a suction nozzle, a brush rotatably mounted therein, and means for frictionally securing said brush in operative position in the nozzle, said means including a downwardly extending post part and a layer of soft rubber interposed between said brush and post for frictionally holding the brush in place while at the same time preventing the transmission of sound and vibration to said cleaner nozzle.

60 3. A suction sweeper including a nozzle having a working mouth at one end thereof, a brush rotatably mounted in the suction mouth, and a mounting for said brush including a pair of posts extending toward the working mouth and bearing means on the brush for frictionally engaging said posts, said means and brush being detachable from the sweeper without disturbing the posts.

70 4. A suction sweeper including a nozzle having a working mouth at one end thereof, a brush rotatably mounted in the suction mouth, and a mounting for said brush including a pair of posts extending toward the working mouth and U-shaped members rotatably mounted at the ends of said brush frictionally engaging said posts, said

U-shaped members and brush being detachable from the sweeper without disturbing the posts.

5. A suction sweeper including a nozzle having a working mouth at one end thereof, a brush rotatably mounted in the suction mouth, and a 5 mounting for said brush including a pair of posts extending toward the working mouth of said nozzle covered with an elastic yielding material and a pair of U-shaped members rotatably mounted at the ends of said brush detachably 10 and frictionally engaging the material covering said posts.

6. A mounting for the rotatable brush of a suction sweeper comprising, bearings in the ends of the brush, a member detachably engaging each 15 of said bearings, said members having sockets remote from the bearings, and cooperating devices carried by the nozzle of the cleaner adapted for reception in such sockets, said devices and members having provisions whereby the brush is 20 frictionally held in place in the sweeper and is removable therefrom along with said members without disturbing said devices.

7. A mounting for the rotatable brush of a suction sweeper comprising, a brush body, bearings inside the ends of the brush body, a member detachably engaging each of said bearings, said members having sockets remote from the bearings, cooperating devices carried by the nozzle 25 of the cleaner and adapted for reception in such 30 sockets, and a member extending through the brush body and engaging said first named members for holding them in alignment.

8. In a suction cleaner, a suction nozzle having a downwardly presented working mouth, vertical posts carried in the working mouth of the cleaner, bushings formed from a flexible yielding material carried by said posts, and a brush carried in the working mouth of the cleaner having parts 35 at its ends for detachably engaging said bushings, said posts at its ends for detachably engaging said 40 bushings.

9. In a suction cleaner, a suction nozzle having a downwardly presented working mouth, posts carried in the working mouth of the cleaner, bushings formed from a flexible yielding material carried by said posts, and a brush carried in the working mouth of the cleaner having parts 45 at its ends for detachably engaging said bushings, said posts being adjustable toward and away from the working mouth of the nozzle.

50 10. In a suction cleaner, a suction nozzle having a downwardly presented working mouth, posts carried in the working mouth of the cleaner, bushings formed from a flexible yielding material carried by said posts, and a brush carried in the working mouth of the cleaner having bearing members 55 at its ends for detachably and frictionally engaging with said resilient bushing.

11. A rotatable brush for a vacuum cleaner comprising an elongated brush body, ball bearings in the ends of said brush body, including concentric inner and outer annular ball races, a centrally bored supporting member projecting from each of the ends of said brush body detachably received in the inner race of said bearings and having a shoulder bearing against the side thereof which faces away from the ends of the brush body, and means inside the brush body 60 detachably received within the bore of each of 65 said supporting members for holding them in alignment with the brush axis.

12. A rotatable brush for a vacuum cleaner comprising an elongated brush body, ball bearings in the end of said brush body, including 70 75

concentric inner and outer annular ball races, a supporting member projecting from each of the ends of said brush body detachably received in the inner race of said bearings and having a shoulder bearing against the side thereof which faces away from the ends of the brush body,

said brush body being formed with a hollow axially extending passageway, and a rod in said passageway slideably fitted into said supporting members for holding them in alignment with the brush axis.

LLOYD W. PARDEE.
